UNITED STATES PATENT OFFICE.

WILLIAM TURNBULL, OF WELLINGTON, NEW ZEALAND.

FLUSHING-VALVE FOR WATER-CLOSETS.

No. 878,166.

Specification of Letters Patent.

Patented Feb. 4, 1908.

Application filed August 6, 1906. Serial No. 329,515.

To all whom it may concern:

Be it known that I, WILLIAM TURNBULL, a subject of His Majesty the King of Great Britain and Ireland, residing at Lambton Quay, Wellington, in the Colony of New Zealand, have invented certain new and useful Improvements in Flushing-Valves for Water-Closets, of which the following is a specification.

10 This invention provides improved means for automatically cutting off the flow of flushing water passing to the pan of a water closet or the like.

According to this invention a water supply 15 pipe communicates with a valve chamber through which passes a valve rod, operable by a handle fixed to a shaft, which passing through a stuffing box, enters a recess formed in a cap upon a down pipe, leading 20 from the valve chamber. An arm secured to the shaft is connected to the valve rod by a coupling link. A stop valve fixed to the valve rod has a seat in the valve chamber, and a sleeve which enters the cap upon the 25 downpipe, and below the stop valve a guide is provided for the valve rod.

A regulating chamber secured to the top 30 of the valve chamber has a perforated bottom plate, through which the valve rod passes. A perforated plunger, fitting loosely upon the upper part of the valve rod, rests upon a shoulder formed upon the rod, and has a valve seating for a regulating valve 35 secured upon the end of the valve rod. The upper end of this rod is hollow and is perforated above its shoulder. A regulating screw having a saw cut through its stem, screws into the hollow top of the valve rod.

The top of the regulating chamber is 40 closed by a screw cap, whereby access is obtained to the regulating screw, and an escape for air provided, when the valve is first brought into use.

The drawing herewith illustrates the invention.

45 Figure 1. is an elevation partly in section, and Fig. 2. a sectional elevation of the flushing valve, and Fig. 3. is a sectional plan on line A—A. and Fig. 4. is a sectional plan on line B—B. Fig. 2.

50 Referring to the drawings:—1 is a water supply pipe communicating with a valve chamber 2, through which passes a valve rod 3, operable by a handle 4, which is fixed to a shaft 5, passing through a stuffing box 6, and 55 entering a recess 7 formed in the cap 8,

secured upon a down pipe 9. An arm 10 secured upon the shaft 5, is connected to the rod 3 by a coupling link 11, and pins 12 and 13. A stop valve 14, integral with or secured to the rod 3, has a leather seating 15, secured in position by a sleeve 16, screwed upon the boss 17 of the said valve. The valve 14 has a seating 18, formed upon the top of the cap 8, and entering the bottom of the valve 60 chamber 2. When the valve 14 is closing upon its seat 18, the sleeve 16 enters the top of the cap 8 into which it fits loosely and thus allows the valve to close without sudden shock. A guide bar 19, is provided in the 65 cap 8 for the rod 3. The regulating chamber 20, is fixed upon the top of the valve chamber 2, and has a perforated bottom plate 21, through which the valve rod 3 passes. A plunger 22 having perforations 23, and fitting 70 loosely upon the upper part of the valve rod 3, rests upon a shoulder 24, formed upon the rod 3, and has a valve seating 25 for a regulating valve 26 screwed upon the end of the 75 valve rod, and provided with a leather seating 27. The upper end of the rod 3, has a recess 28, and radial perforations 29 leading into the said recess. A regulating screw 30 having a saw cut 31, screws into the top of the recess 28. A screw cap 32 closes the top 80 of the regulating chamber.

The flushing of a water closet is effected by raising the handle 4 to lift the valves 14 and 26 from their seats 18 and 25 respectively, to allow water to flow through the cap 8, and 85 down pipe 9. The shoulder 24 raises the plunger 22, which then passes upwards with the valve 26 raised from its seats 25 as clearly shown in Fig. 2, to allow free passage through the plunger 22 of water contained in the 90 upper part of chamber 20. Upon the operator releasing the handle 4, the valves 14 and 26 fall by gravity assisted by the flow of water through the chamber 2, and the descent of the valve 14 is checked by the valve 26 closing 95 upon its seat 25, and thus shutting off the flow of water through the perforations 23. Water below the plunger 22 then finds its way through the radial holes 29, which are 100 now exposed below the plunger 22, as clearly 105 shown in Fig. 1. The water finds its way through the holes 29 to the recess 28 and thence through the saw cut 31 in the screw 30 to the upper part of the regulating chamber.

110 The flow of water and the descent of the plunger are regulated by adjusting the screw

30, and thus exposing more or less of the saw cut 31 above the top of the valve 26.

What I do claim and desire to secure by Letters Patent of the United States is:—

5 1. For the purpose indicated, a flushing valve comprising in combination, a valve chamber, a downpipe cap secured to the bottom of the valve chamber, a seating upon the cap, and entering the valve chamber, a regulating chamber secured to the valve chamber, a perforated bottom to the regulating chamber, a valve rod having a recess in its upper end and radial holes communicating with the recess, the said rod passing 10 through the valve chamber and into the regulating chamber, a stop valve within the valve chamber rigidly with the valve rod, a perforated plunger fitting loosely upon the upper end of the valve rod and resting upon a 15 shoulder formed on the valve rod, a valve seating upon the plunger, a regulating valve fixed to the top of the valve rod, means for regulating the flow of water through the recess of the valve rod, and means for operating the 20 valve rod; substantially as set forth.

2. For the purpose indicated, a flushing valve comprising in combination, a valve chamber, a downpipe cap secured to the bottom of the valve chamber, a seating upon 25 the cap and entering the valve chamber, a regulating chamber secured to the valve chamber, a perforated bottom to the regulating chamber, a valve rod having a recess in its upper end and radial holes communicating 30 with the recess, the said rod passing through the valve chamber and into the regulating chamber, a stop valve within the valve chamber rigidly with the valve rod, a perforated plunger fitting loosely upon the 35 upper end of the valve rod and resting upon a shoulder formed on the valve rod, a valve 40 seating upon the plunger, a regulating valve fixed to the top of the valve rod, means for regulating the flow of water through the recess of the valve rod, and means for operating the valve rod; substantially as set forth.

seating upon the plunger, a regulating valve fixed to the top of the valve rod, a screw having a saw cut through its stem and fitting the recess in the valve rod, a screw cap closing the top of the regulating chamber, and means for operating the valve rod, substantially as set forth. 45

3. For the purpose indicated, a flushing valve comprising in combination, a valve 50 chamber, a downpipe cap secured to the bottom of the valve chamber, a seating upon the cap and entering the valve chamber, a regulating chamber secured to the valve chamber, a perforated bottom to the regulating chamber, a valve rod having a recess in its upper end and radial holes communicating with the recess, the said rod passing through the valve chamber and into the regulating chamber, a stop valve within the valve 55 chamber rigidly with the valve rod, a perforated plunger fitting loosely upon the upper end of the valve rod and resting upon a shoulder formed on the valve rod, a valve seating upon the plunger, a regulating valve fixed to the top of the valve rod, means for regulating the flow of water through the recess of the valve rod, a shaft entering a recess in the cap of the downpipe, a stuffing box on the downpipe and through which the shaft passes, a 60 handle upon the shaft, an arm within the recess and fixed to the shaft, and a link and pins coupling the arm to the valve rod, substantially as set forth. 65

In testimony whereof I have signed my 70 name to this specification in the presence of two witnesses.

WILLIAM TURNBULL.
